UNITED STATES PATENT OFFICE.

WILLIAM F. OLIN, OF CHICAGO, ILLINOIS, ASSIGNOR TO WILLIAM DEERING,
OF SAME PLACE.

GRAIN-BINDER.

SPECIFICATION forming part of Letters Patent No. 375,830, dated January 3, 1883.

Application filed October 19, 1880. Serial No. 216,655. (No model.)

To all whom it may concern:

Be it known that I, WILLIAM F. OLIN, of Chicago, Cook county, Illinois, have invented certain new and useful Improvements in Self-Binders, of which the following is a description, reference being had to the accompanying drawings, making a part of this specification.

Referring to the accompanying drawings, Figure 1 is a rear elevation of a binding-machine having my improvements incorporated therein. Fig. 2 is a top plan view of the same, the deck, breast-plate, and other parts foreign to my invention being omitted. Fig. 3 is a side elevation of a portion of the clutch mechanism. Fig. 4 is a top plan view of the same. Figs. 5 and 6, a side view and a top plan view of details of the clutch-tripping devices.

Referring to the drawings, A is the binder-frame of the well-known Appleby type having horizontal arms at the top and bottom to support the knotter driving-shaft A' and the needle-carrying shaft A''. The needle-carrying shaft A'' has at one end a fixed-crank, A³. The knotter-shaft A' has fixed on its rear end the gear A⁴, provided with a wrist or crank pin, A⁵, which is connected by a pitman, B, with the crank of the needle-shaft, so that at each revolution of the gear A⁴ the needle receives an upward and downward vibration, as in existing machines.

C represents the horizontal crank shaft, by which the packers are carried as usual. This shaft is mounted in suitable bearings in the frame and will receive a constant rotation through driving mechanism of any appropriate character.

D is the trip and compressor-shaft mounted horizontally in bearings in the frame and provided with the trip and compressor D², and with a crank, D' at the rear end, both parts being fixed rigidly thereon. The gear A⁴ is formed with an irregular cam, E, on its side face. This cam engages and moves an anti-friction roller, F², mounted on one end of an arm, F', pivoted to the frame at the point F lying between the frame and the gear A⁴. The relative positions of the cam and the wrist A⁵ are such that during the advance of the needle the compressor is elevated and moved toward the same to assist in the compression of the gavel, and finally

at the proper time the compressor is released and permitted to fall in order that the bundle may escape, these actions being essentially the same as in other machines already known in the art.

55

In order that the compressor may oppose the needle elastically or with a yielding resistance, I provide the moving end of the lever F' with a socket or barrel, F³ containing and supporting one end of a spiral compression spring, F⁴. The upper end of the compressor operating pitman G is jointed to the lower end of the stem or spindle F⁵, which is extended upward through the barrel and the spring, and provided at its upper end with a nut, F⁶, bearing on the spring and serving as a means for regulating its tension, so that the compressor may be sustained with more or less force, as the character of the grain may demand. When the compressor meets with excessive pressure, the spring F⁴ will yield, and, allowing the pitman G to descend, will permit the retreat of the compressor.

65

The pitman G is preferably formed with a lateral wrist at its upper end, extending through and beyond the spindle F⁵, for connection with the tripping devices, as will be presently explained.

70

The packer-shaft C, as before mentioned, is driven constantly, and is provided with a sprocket-wheel, C', connected by an endless chain, C², with a second sprocket-wheel, C³, mounted on a stud, C⁵, on the binder-frame, and receiving a constant rotation. On the stud or axis of the pinion C⁵ is mounted loosely a pinion, H, which engages and communicates motion to the main gear A⁴. The pinion H carries the dog H', pivoted thereto. This dog has a shoulder, against which the semi-friction rollers H², mounted on the sprocket-wheel C³, engage when the parts are in operative position. The dog is acted upon by a spring, H⁴, which has a tendency to keep it in position to engage the rolls. When thus engaged, the dog communicates motion from the sprocket-wheel to the pinion H, and thence to the main gear and knotter-shaft in a familiar manner.

and to be disengaged at proper times differs from the others at present known in the following particulars:

Pivoted to the main frame, preferably concentric with the arm F', is the detent I, adapted to reach upward and engage the outer end of the dog or pawl H' and throw the same out of engagement, in order to stop the motion of the pinion H. The detent I has an arm extended rearward beneath the knotter-driving shaft A', terminating in the foot I', which underlies a cam, I², formed on the hub of the main gear A⁴. The detent I is also formed with a second arm, I³, extending rearward and pivoted upon the journal which connects the pitman G to the spindle F⁵.

The operation of these parts is as follows: The rotation of the packer-shaft C causes the packers to compact the gavel against the compressor D², while the pinion H and the main gear A⁴ remain at rest. The compression of the accumulating gavel against the compressor D² forces the latter backward, and, rocking its shaft D, causes the arm D' to pull the pitman G downward against the resistance of the spring F⁴. The pitman in its descent acts, through the arm I³, to throw the detent I out of engagement with the dog H', whereupon the dog, engaging one of the rollers on the wheel C³, causes motion to be transmitted through pinion H to the main gear A⁴ and its cam. The rotation of the main gear through the parts before described causes the needle to be brought forward and the compressor to be advanced in the opposite direction. As the pinion H makes four revolutions while the gear A⁴ makes one, the detent I must be retained in such position that the dog H' will not strike it and disengage the clutch until the pinion has completed its fourth revolution, so as to complete the binding operation. The rotation of the gear A⁴ causes its cam I² to bear on the foot of the arm I' of the trip I and hold it down, and thus it is that the detent is kept out of action. At the termination of the binding operation the cam I is carried clear of the detent, and the latter, under the action of the spring, disengages the clutch mechanism.

In order to keep the binding mechanism in its normal position and prevent the wheel A⁴ from starting backward, as it frequently occurs with this form of clutch, I mount the spring-actuated pawl K on the wrist A⁵ of the main gear, the form and proportion of this pawl being such that when the gear A⁴ reaches the

proper position of rest the dog falls behind and bears against the axis C⁵ of the pinion H, as shown in Fig. 1.

I am aware that grain-binding machines driven through a clutch which was disengaged by a detent have been provided with automatic means for holding the detent out of action until the completion of the binding action; but I believe myself to be the first to mount a cam on the shaft of the main gear-wheel and arrange it to act on the detent.

Having thus described my invention, what I claim is—

1. In a grain-binder of the Appleby type having an overhead knotter-driving shaft, the combination of the main gear-wheel A⁴, fixed on the knotter-shaft, its driving-pinion H, the continuously-rotating driving-wheel C³, concentric with the pinion, the clutch devices to connect the driving wheel and pinion, the detent I, to hold the clutch out of action, and the cam I², carried by the knotter-shaft, and acting directly on the detent to hold it out of engagement with the clutch, whereby the knotter-shaft is enabled to directly control the period of action of its driving-clutch.

2. The gear A⁴, mounted on the knotter-driving shaft, the driving-pinion engaging directly therein, and the continuously-rotating driving-wheel C³, concentric therewith, in combination with the clutch-dog to connect said wheels, the clutch-tripping arm I, acting at one end directly on the dog, the compressor-operating spring acting directly on the arm to cause its engagement, and the cam on the knotter-driving shaft also acting directly on the arm to hold it out of engagement.

3. The detent I, having arm I³, and the stem or spindle F⁵, and its encircling spring, in combination with the positively-actuated compressor-actuating lever F', sustaining the spring, and the compressor-pitman connected at one end to both the lever and the detent.

4. The compressor-operating lever, the spring receiving support therefrom, and the stem or spindle passing through the spring, in combination with the detent-lever I, and compressor-actuating pitman having one end connected with both the stem and the detent by a single wrist or journal.

WILLIAM F. OLIN.
